UNITED STATES PATENT OFFICE.

JOHN PLAYER, OF CHICAGO, ILLINOIS, ASSIGNOR TO AMERICAN LOCOMOTIVE COMPANY, OF NEW YORK, N. Y., A CORPORATION OF NEW YORK.

LOCOMOTIVE-CYLINDER.

SPECIFICATION forming part of Letters Patent No. 696,484, dated April 1, 1902.

Application filed November 7, 1901. Serial No. 81,476. (No model.)

To all whom it may concern:

Be it known that I, JOHN PLAYER, of Chicago, in the county of Cook and State of Illinois, have invented a certain new and useful 5 Improvement in Locomotive - Cylinders, of which improvement the following is a specification.

My invention, while applicable to steam-engine cylinders of other forms, relates more 10 particularly to locomotive - cylinders of the "half-saddle" type—that is to say, those that are cast integral with one section or half of a saddle or bed-plate—upon which the smoke-box of the boiler is supported and through 15 the intermediation of which it is connected to the engine-frames.

In locomotive-cylinders of the above type the steam and exhaust passages are formed 20 in the saddle-sections, and the exhaust-passage of each cylinder terminates in a single opening in the top of the saddle-section of said cylinder, the exhaust-pipe, which may be either single or double, being secured to the saddle-sections above their exhaust-openings. In the case of cylinders whose distribution-valves provide for internal admission 25 by internal edges and exhaust by external edges there occurs the overpassage of the exhaust-steam from one end of the cylinder through the exhaust-cavity to the other end. This overpassage of the exhaust-steam tends 30 to retard its emission from the blast or exhaust nozzle by reason of its re-expansion in the enlarged exhaust-chamber during its passage from the distribution-valve to the blast-orifice and necessitates a decrease in the area 35 of the latter in order to maintain a desired degree of vacuum in the smoke-box of the locomotive. A further result of this overpassage of the exhaust-steam is to muffle or 40 deaden the sound which it makes in its escape, the effect of which has been to prejudice enginemen and others against locomotives in which it occurs and to lead persons 45 so prejudiced to the belief that the performance of the engines is not fully satisfactory and to induce them to further reduce the area of exhaust-orifices thereon in order to produce a sharper sound, harmonizing with 50 that which is made in the operation of simi-

lar engines the internal exhaust-passages of which are smaller and more direct and which do not permit of the re-expansion of the exhaust-steam in its passage from the valve to the exhaust-orifice.

The object of my invention is to provide a cylinder of the type referred to in which the steam may be exhausted at the ends of the distribution-valve without involving the objectionable results above stated and which shall be desirably adaptable to application in locomotives of the various types now known in practice without involving complication or increased cost in construction or maintenance.

The improvement claimed is hereinafter fully set forth.

In the accompanying drawings, Figure 1 is a side view in elevation of a half-saddle locomotive - cylinder embodying my invention; Fig. 2, a plan or top view of a pair of cylinders connected in operative relation; Fig. 3, a vertical transverse section through the cylinders of Figs. 1 and 2, the right-hand half being taken on the line *a a* of Fig. 4 and the left-hand half on the line *b b* of said figure; Fig. 4, an inclined longitudinal section on the line *c c* of Fig. 3, and Fig. 5 a partial transverse section showing the application of an exhaust-pipe.

My invention is herein exemplified as applied in a cylinder saddle-section 12, which accords with those now in approved service in the general particulars of being a casting of box or chambered form, having a steam-cylinder 12^a on its lower end, at the outer portion thereof, a distribution-valve chest 12^b, adapted to receive a piston distribution-valve adjoining the cylinder and communicating therewith near each of its ends by a port 12^c, and a bed or supporting plate 12^d, curved to fit the periphery of a locomotive smoke-box on its top. A suitably-flanged vertical web 12^e, which abuts against a similar web on a counterpart casting, is formed on the inner side of the saddle-section, or that which is farther from the cylinder, and the two saddle - sections are connected in the erection of the locomotive in the ordinary or in any suitable and preferred manner.

In the practice of my invention a steam-inlet passage 13 is formed in the saddle-section, said passage leading from the top plate 12^a (at which it is, as usual, open for connection to one of the steam-pipes) to the central portion of the distribution-valve chest 12^b. An independent exhaust-passage 14 is formed in each end of the saddle and leads from the adjacent open end of the distribution-valve chest 12^b, with which it communicates directly and fully to an exhaust discharge-opening in the top plate 12^a. The discharge-openings of the two exhaust-passages 14 are located closely adjacent one to the other and to the inner web of the saddle-section, so that when the two sections are connected for attachment to the engine-frames the four discharge-passages may be inclosed by a single exhaust-pipe casting 15, secured to the top plate 12^a. It will, of course, be understood that the openings in the saddle-section at the lower ends of the discharge-passages 14 are closed by suitable removable heads or caps after the distribution-valve and its stem have been inserted in the valve-chest 12^b. The particular form of exhaust-pipe employed does not in and of itself constitute an essential part of my present invention, and any known and suitable construction thereof may be applied in the discretion of those skilled in locomotive-building. The exhaust-pipe 15 herein shown is provided with four openings in its base, corresponding in form and relative location with the four discharge-openings of the connected saddle-sections, and may either terminate in a single blast-opening at its top or in any other suitable blast-discharge appliance. An exhaust-pipe of this construction is deemed by me to be preferable; but it will be obvious that one having either a single opening in its base, communicating with all four of the discharge-openings, or two openings separated by a central partition, each of said openings communicating with the discharge-openings of one of the saddle-sections, is equally applicable.

I claim as my invention and desire to secure by Letters Patent—

1. A locomotive-cylinder saddle-section in which are formed an upper bed-plate, a lower cylinder, a valve-chest communicating, by ports, with the ends of the cylinder, a steam-supply passage leading from the bed-plate to the central portion of the valve-chest, and exhaust-passages leading from the ends of the valve-chest to independent discharge-openings in the bed-plate. 55

2. A locomotive-cylinder saddle-section in which are formed an upper bed-plate, a vertical inner web for connection to a counterpart saddle-section, a cylinder located on the outer and lower portion of the section, a valve-chest communicating, by ports, with the ends of the cylinder, a steam-supply passage leading from the bed-plate to the central portion 65 of the valve-chest, and exhaust-passages leading from the ends of the valve-chest to independent discharge-openings in the bed-plate located adjacent one to the other and to the inner web. 70

3. The combination of two locomotive-cylinder saddle-sections, each having an upper bed-plate, a vertical inner web for connection to a counterpart saddle-section, a cylinder located on the outer and lower portion of the section, a valve-chest communicating, by ports, with the ends of the cylinder, a steam-supply passage leading from the bed-plate to the central portion of the valve-chest, and exhaust-passages leading from the ends of the valve-chest to independent discharge-openings in the bed-plate, located adjacent one to the other and to the inner web, and an exhaust-pipe connected to the saddle-sections and having four lower openings, each communicating with one of the exhaust-passage discharge-openings. 85
